UNITED STATES PATENT OFFICE.

JOHN T. CLARK, OF PROVO, UTAH.

RAILWAY-TIE AND FASTENER.

1,010,587.

Specification of Letters Patent.

Patented Dec. 5, 1911.

Application filed April 1, 1911. Serial No. 618,434.

To all whom it may concern:

Be it known that I, JOHN T. CLARK, a citizen of the United States, residing at Provo city, in the county of Utah and State 5 of Utah, have invented certain new and useful Improvements in Railway-Ties and Fasteners, of which the following is a specification.

The purpose of my invention is to provide 10 a railway tie, and a fastener to secure the rails thereon, which will have the sustaining surface necessary for the rails, and one having the central portion so formed as to prevent lateral movement of the tie.

15 A further object is to provide such a tie and fastener therefor as will prevent lateral and longitudinal displacement of the rails, and any tendency to bend at the joint of the rails, and also to provide a perfectly 20 insulated rail for use in the block signal system.

A further object is to provide a railway tie and fastener on, and by which the rails may be secured and removed within less 25 time than now is required.

Other objects and advantages will appear from the following specifications and drawings, forming a part hereof.

In said drawings similar figures of reference indicate like parts throughout the several figures.

Figure 1 is a side elevation of one end of the tie, with the rail and parts of the insulation in section. Fig. 2 is a vertical longitudinal section of one end of the tie and fastener, on line *a a* Fig. 4. Fig. 3 is a plan of one end of the tie and a central portion of a rail thereon. Fig. 4 is a plan of one end of the tie, with a portion of two rails at the 35 joint, also a central portion of one of the bridge fish-plates. Fig. 5 is an end elevation of three of the ties, and a side elevation of the bridge fish-plates, parts cut away. Fig. 6 is a plan of the tie, with rails 40 and insulation removed. Fig. 7 is a plan of one end of the tie, with the straps removed, parts cut away.

My tie is made of sheet metal, bent to form an upturned channel 1. Near each end a 50 section of the sides of said channel is cut away, and metal straps 2, are transversely placed therein, forming a partial cover for said channel 1, and between said straps 2, the sides of said channel 1, are further 55 cut away. The metal portion of the bottom of said channel 1 has H-shaped cuts or slits

3 therein, and the inner or tongue parts of said cuts are each bent downward at right angles to the bottom of the tie, thus forming depending lugs 3', the purpose being to 60 embed said lugs 3' in the road-bed, and prevent lateral displacement of the tie. Said straps 2 have vertical slots 4 cut therethrough, preferably at an angle of about 45 degrees from the longitudinal of the tie. 65 Within the covered portions of the tie are placed short blocks of wood or other fibrous material 5, the upper side of which extends above the edges of the deeper cuts in the sides of said channel. Over the said blocks 70 5, and within said covered portions of the tie, are placed metal rail plates 6, having vertical slots 7 cut therethrough, preferably at an angle of about 45 degrees from the longitudinal axis of the tie, and vertically 75 alined with the said slots 4 in the straps 2. The purposes of said blocks of wood are; first, to provide a certain amount of resiliency or cushion effect under the rails A, second, to hold the bolt or spike that is to be 80 driven through the slots 4 and 7 and into the said block of wood. At each end of each of said blocks 5 and within the covered portion of the tie, and between the said rail plates 6 and the said straps 2 is driven one 85 portion of a bracket-shaped metal wedge 8, having the inserting edge thereof tapered to engage and slide on the upper side of the flange of the rail. The vertical portion of said bracket-shaped wedge 8 covers the outer 90 end of said wooden block, and is made the same length as the distance between the upper side of the bottom of said channel 1 and the lower side of said straps 2. Cut through the horizontal portion of each of 95 said bracket-shaped wedges 8, are slots 9, preferably at an angle of about 22 degrees from the longitudinal, and so alined with the said slots 4 and 7, that when the said wedges are being driven into place, some part 100 of said slot 9 will be in vertical alinement with said slots 4 and 7. If desired, two of said series of slots 4, 7 and 9 may be placed on one side of the rail. When a bolt or spike 10, having a flanged head 11, and with the squared portion 12 adjacent to said flange, is inserted through the said slots 4, 7 and 9, the wedge 8 cannot be removed until the said bolt is withdrawn. To prevent the said bolts or spikes 10 from being jarred from slots 4, 7 110 and 9 by the vibrations caused by passing trains, the lower end of the said bolt is

driven a short distance into the said wooden block 5. The squared portion 12 of the said bolt 10 is of a length equal to the thickness of said straps 2, and each side of the square 5 is the same width as the width of the said slots 4 and 7. This prevents any tendency of the said bolt 10 to roll. To prevent water, either rain or melted snow from entering through the said slots and injuring 10 said blocks 5, a washer 17 is carried on each of said bolts 5, shaped to cover the said slot 4.

Placed on the outside and at the juncture of two rails A, and bolted thereto by the 15 bolts 15 is the bridge fish-plate 13. The upper side of said bridge fish-plate is placed flush with the tread of the rails. The said bridge fish-plate is made of length sufficient to transversely cross or cover three of my 20 ties, when the ties are in place on the road bed. At each tie, and held by the bolts 15, is placed a brace-block 14, having a shoulder 16 cut near each end, forming a depending lug, which fits over the edge of the said 25 channel 1. The purpose being that when said bridge fish-plate and the brace-blocks are in position and firmly bolted to the rails, any longitudinal movement of the rails will be prevented. If it is desired to insulate the 30 rails, a strip of insulating material 18, is placed under the rail, the bridge fish-plate and the brace-block, and over the tie and other parts of the fastener. The said bridge fish-plate, covering at it does three ties, prevents any vertical movement of the ends of 35 the rails, when the train passes over that part of the track, and the consequent breaking of the insulation. The different angles of the slots 4, 7 and 9 form a different opening or hole for said bolt or block at each 40 position of the said wedge, as it is inserted or withdrawn thus enabling me to fasten the said wedge at any position, and to form a spring tension clamp for rails of various 45 weights, or thickness, or width of flanges, and to take up any shrinkage from wear or otherwise, of said wooden blocks 5. Also I provide a hole for the spike or bolt that is adjustable in position.

50 Having thus described my invention, I desire to secure by Letters Patent and claim:

1. A railway tie and fastener consisting of an upturned channel formed from a sheet of metal, having transverse channels cut in the 55 upper edges thereof, the central portion being deeper than the other portions, transverse metal straps riveted to said upturned channel within the shallower of said transverse cuts and having vertical slots cut therein at an angle of about 45 degrees from the longitudinal of said upturned channel, a wooden block closely fitted within said channel near each end thereof, metal rail plates 60 also fitted within said channel and covering said wooden blocks and having vertical slots

therein similar to and alined with the slots in said metal straps, metal bracket-shaped wedges having vertical slots therethrough at an angle of about 22 degrees from the longitudinal and adapted to fit within said channel and between said rail-plates and said transverse straps, and spikes having a flanged head and squared portion adjacent to said head adapted to be driven through 70 said slots.

2. A railway tie and fastener consisting of an upturned channel formed from a sheet of metal and having transverse channels cut in the edges of said upturned channel, transverse metal straps riveted to said upturned 80 channel and within two of said transverse channels, and having slots therethrough at an angle of practically 45 degrees from the longitudinal of said upturned channel, a cushion block closely fitted within each end 85 of said upturned channel, metal rail plates having slots therethrough alined with the slots in said metal straps, metal wedges having slots therethrough practically at an angle of 22 degrees from the longitudinal, and 90 bolts adapted to be driven through said slots and engage in said cushion blocks.

3. A railway tie and fastener consisting of an upturned channel formed from a sheet of metal and having transverse channels cut 95 in the edges of said upturned channel, transverse metal straps riveted to said upturned channel and within two of said transverse channels, and having slots therethrough at an angle of practically 45 degrees from the longitudinal of said upturned channel, a cushion block closely fitted within each end 100 of said upturned channel, metal rail plates having slots therethrough alined with the slots in said metal straps, metal wedges having vertical slots therethrough practically at 105 an angle of 22 degrees from the longitudinal, the said slots adapted to form an opening adjustable in position, and spikes adapted to be driven through said slots and engage said 110 cushion blocks.

4. A railway tie and fastener consisting of an upturned channel formed from a sheet of metal having slits cut in the bottom of said channel, depending lugs formed by bending the inner parts of said slits downward, transverse metal straps riveted to the upper edges of said channel, and having slots therethrough at an angle of practically 45 degrees from the longitudinal of the said 115 upturned channel, a cushion block fitted within each end of said channel, metal rail plates having slots therethrough alined with the slots in said metal straps, metal wedges having slots therethrough practically at an angle of 22 degrees from the longitudinal, spikes adapted to be driven through said 120 slots and into said cushion blocks, and insulating means between said rail plates and wedges, and the rail to be used on said tie. 125 130

5. A railway tie and fastener consisting of an upturned channel formed from metal sheets, depending lugs formed by bending the inner parts of slits cut in the bottom of 5 said channel at right angles to said bottom, metal straps riveted to the upper edges of said channel and having slots cut therethrough at an angle of practically 45 degrees from the longitudinal of the said channel, a cushion block fitted within each end of 10 said channel, metal wedges having slots cut therethrough practically at an angle of 22 degrees from the longitudinal and adapted to be driven between said cushion blocks and said metal straps, spikes adapted to be 15 driven within said slots into said cushion blocks, and insulating means between the tie and fastener and rails to be placed thereon.
- In testimony whereof I have affixed my signature in presence of two witnesses.
- JOHN T. CLARK.
